UNITED STATES PATENT OFFICE.

JOHN J. SIMMONDS, OF IOLA, KANSAS.

HYDRAULIC VALVE.

1,103,320.

Specification of Letters Patent. Patented July 14, 1914.

Application filed January 13, 1913. Serial No. 741,804.

To all whom it may concern:

Be it known that I, JOHN J. SIMMONDS, a citizen of the United States, residing at Iola, in the county of Allen and State of 5 Kansas, have invented certain new and useful Improvements in Hydraulic Valves; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to valves, and more particularly to a valve for controlling flow to a hydraulic press, or the like, the principal use for which the valve is contemplated being in connection with a press for forming fire clay retorts commonly used in zinc or like ore smelters.

20 While the press, or other mechanism with which the valve is used, is not claimed as a part of the present invention, I have illustrated a well known form of retort press in order to better explain and illustrate the construction and operation of my improved valve, and will describe whatever parts of the press it is necessary to mention in connection with the description of the valve.

25 In the operation of a press of the character shown, that is, a press comprising a ram for forming a retort chamber and a ring for packing the sides of the retort and wherein 30 the ram is operated by a large plunger and the ring by a pair of small plungers, it is the practice to feed water under pressure to the plunger chambers so that the small plungers are operated in unison and independently of the large plunger.

35 It is also an object of the invention to provide a valve wherein flow is automatically admitted to the ram plunger chamber when a certain predetermined pressure is on the 40 ring plungers, in order that the ram may be supported independently of the ring plungers to enable the parts to equalize.

45 It is also an object of the invention to provide a valve through which communication 50 is afforded between the ram plunger chamber and a supply tank during the initial travel of the ram and ring plungers, and whereby the relatively idle travel of the ram will serve to draw water from the tank into

its chamber, to fill the vacuum created in the 55 chamber by the lifting of the plunger and thereby save pumping that amount of water.

It is also an object of the invention to provide a valve whereby the plunger chambers 60 may be drained quickly in order to release the ram and ring plungers when the formed retort is completed.

In accomplishing these and other objects of the invention, which will be mentioned in the following description, I have provided the improved details of structure hereinafter described and illustrated in the accompanying drawings, wherein:—

Figure I is a side elevation of a valve constructed according to my invention. Fig. 70 II is a central vertical section of same. Fig. III is a plan view of same. Fig. IV is an end view of same. Fig. V is a section on the line V—V, Fig. I, showing the divided conduit around the drain valve. Fig. VI is a 75 central vertical section of either of the check valves showing the edge channels for obviating vacuum in the guide chambers. Fig. VII is an elevation of the valve and its operating mechanism, shown in combination 80 with a retort press of ordinary construction, part of the press being in section. Fig. VIII is a central vertical section of the press.

Referring more in detail to the parts, and first to the press or machine with which 85 the valve is used in order that the construction and operation of the valve may be better understood, 1 designates the mold chamber (Figs. VII and VIII) within which the retorts are formed, and 2 the caps for exposing the upper portion of the mold, the cap levers and locking devices being such as are ordinarily used in machines of this character.

3 designates the ram which is connected 95 with a plunger 4 that extends into a chamber 5 which is fed by a pipe 6 that leads to the valve, and through which water under pressure is delivered in order to operate the ram.

100 7 designates a ring which surrounds the ram and is adapted for packing the soft fire clay in the mold and pushing the retort from the press and is operated by a slotted sleeve 8 that is mounted on a cross head 9 which is 105 operably connected with the plungers 10 that extend into the cylinders 11, the cylinders 11 being smaller than the ram cham-

ber 5 and fed by separate pipes 12 which also lead to the valve, as will presently be more specifically described.

The ram 3 carries a key 13 which extends through slots 14 in the sleeve 8 and is adapted for engagement by the upper portions of the cross head so that when the latter is lifted under pressure in the chambers 11 the ram is lifted therewith, although the sleeve 13 may be lowered away from the ram when the latter is held by pressure in the chamber 5.

The valve comprises a casing 15 having a bore 16 fed by a pipe 17 which leads to a pump (not shown) which may be connected with a supply tank (also not shown). In the bore 16 are valve seats 18 and 19, and slidably mounted in glands 20 and 21, and adapted to seat in the valve seats 18 and 19 respectively, are plunger valves 22 and 23. The valves 22 and 23 extend from the glands 20 and 21 and are connected with the lever 24 at opposite sides of a fulcrum 25, so that they are worked oppositely to each other, one being closed when the other is opened. The lever 24 is preferably connected by a rod 26 with a quadrant 27 located above an operating floor F, of the type usually found in smelters, around the retort press.

The channel 16 continues through the valve seat 19 and through the channel 28 of a check valve 29 which is adapted for preventing back flow to the pump, and preferably comprises a head 30 adapted to seat on the valve seat 31 and having a stem 32 projected into a pocket 33 in a plug 34 that is screwed into the valve casing, the stem 32 having a channel 35 and cross channel 36, through which fluid may pass to the pocket 33 to obviate vacuum in the pocket which might interfere with the proper operation of the valve.

The feed channel has branches 38 leading from the valve channel 28 to the supply pipes 12 which lead to the small plunger chambers of the press which control the operation of the forming ring. The channels 38 extend around a drain valve, presently described, and lead to the channel 39 of the spring-checked valve 40 which is adapted to seat on a seat 41 to cut off flow through the feed conduit to the ram chamber. The spring check, by which the valve 40 is controlled, preferably comprises a toggle 42, one link 43 of which is pivotally mounted on a rod 44 carried by a frame 45, and the other link 46 extended into a casing 47 which is pivotally mounted on said frame 45. The valve 40 is connected with the link 43, and said link has a rod 48 leading through the floor F and provided with a handle 49 by which the toggle may be broken downwardly to reseat the valve.

The spring 50 on the link 46 is adjustable to yield under a predetermined pressure so

that when the ring in the retort press has compressed the clay, pressure is exerted back on the plungers sufficient to overcome the tension for which the spring is set, and fluid in the valve conduits lifts the valve 40 to straighten the toggle and break same upwardly and thereby free the channel through the valve seat 39.

A channel 52 leads from the valve channel 39 through a check valve channel 53 and to the pipe 6 which supplies the ram plunger 5, so that when the predetermined pressure has been reached on the ring plungers, the ram channel is automatically opened and water forced into all of the chambers under the same pressure, it being apparent, however, that as the chamber 5 is of greater area than chambers 11 that greater pressure will be exerted on the ram plunger than on the ring plungers.

A check valve 56, preferably of the same construction as the check valve 29, heretofore described, is located in the valve channel 53 and adapted to seat on a seat 57 communicating with a channel 58 which leads back to a supply tank (not shown) through a pipe 59 so that when the ram plunger is lifted by the ring plungers and the vacuum is created in the ram plunger chamber the vacuum causes the check valve to lift so that water may be drawn from the tank into the ram plunger chamber to fill the vacuum and thereby save pumping that amount of water, which is a large gain of time in each operation of the press and thus saves the use of a low pressure accumulator.

When the retort has been formed and it is desired to drain the chambers, a valve 60 is operated, so that its head 61 is lifted from its seat 62 to establish communication between the feed channel in the valve and a drain channel 63 leading to the pipe 59 that connects with the supply tank. In order to drain the chambers quickly I provide an ejector 64 the discharge from which is connected with the tank and pressure supplied from the pump through the seat 18 controlled by the plunger valve 22, when the valve is opened and its oppositely operable valve 23 is closed to close the valve channel. The drainage or release valve may be operated by a rod 66 which also extends through the floor F so that it, as well as the other control members, may be operated conveniently.

In using the valve, presuming the parts to be constructed and assembled as described, and, for the sake of illustration, connected with a press for making retorts, when the press is ready for use the drainage or releasing valve 60 is closed and the valve lever 24 is rocked to seat the plunger valve 22 and unseat the valve 23, so that fluid pumped into the valve will travel through the channel 16, past the valve seat 19 and

into the channel 28, where it lifts the check valve 30, and through the by-pass channels 38 to the pipes 12 through which it is delivered to the ring plunger chambers, the flow of fluid through the channel 39 being cut off by the spring check plunger valve 40. When the ring plungers are raised by the hydraulic pressure they also lift the ram 3 through the connection made by key 13 so that the ram and plungers rise together to form the retort chamber and pack the material. When the material has become packed to resist a predetermined pressure (usually 1000 lbs.) the spring check controlling the plunger valve 40 is overcome by the pressure against the valve 40 so that the valve is lifted and the check toggle reversed, so that the plunger valve 40 is held in open position. The fluid then flows through channels 39 and 52 around the check valve 56 and through the pipe 6 into the ram plunger chamber, so that the ram is controlled by hydraulic pressure independently of the ring plungers. It is apparent that when the ram plunger is raised by the ring plungers the vacuum created in the ram plunger chamber would interfere with the proper lifting of the plungers unless means were provided for admitting fluid to fill the vacuum in the chamber, such means in the present instance comprising a connection through the pipe 6, the check valve 56, conduit and pipe 59 to the tank (not shown) from which the fluid for operating the press is drawn, it being apparent that when the vacuum in the ram plunger chamber is sufficient to overcome the check valve 56 the valve will be lifted and water drawn from the tank into the plunger chamber to relieve the vacuum and save pumping that amount of water which is a great saving of time in each operation of the press. When the water has been turned on to the ram chamber the parts operate in the usual manner until the retort is formed, when the fluid is turned off the press by rocking the valve lever 24 to seat the plunger valve 23 and lift the valve 22, so that the pump, which operates continuously, will force water through the idle channel leading from the valve seat 18 to the tank pipe 59, and in order to quickly reverse the ram and ring plungers I provide the ejector 64 which is reduced in size enough to create sufficient pressure for delivering the water from the idle passage into the tank pipe, so that the contents of the plunger chambers is drawn out of the chambers to hasten their relief, both the ram and ring plunger chamber being drained through the channel 63 when the drainage or release valve 61 is operated to establish communication between the ram and ring plunger conduits after the plunger valves 22 and 23 have been reversed. In order to obviate possible back leakage dur-

ing the manipulation of the valves, or at any other time, I provide a check valve 30 in the channel 28 between the plunger supply pipes and the plunger valve 23, so that should pressure in the press exceed that in the pump the fluid cannot be driven back from the press to the pump. 70

Having thus described my invention, what I claim as new therein and desire to secure by Letters-Patent, is:— 75

1. The combination with a valve casing, of conduits leading from the casing, means for supplying fluid under pressure to the casing, means for draining the casing and conduits and valve mechanism for diverting the fluid supply from the conduits to the drain and whereby fluid is drawn back from the conduits, substantially as set forth. 80

2. The combination with a valve casing, of means for conducting fluid under pressure to the casing, conduits for conducting said fluid from the casing, a drain communicating with said conduits and with the supply means and comprising an ejector, and valve mechanism whereby said fluid is diverted from the conduits to the drain through said ejector, for the purpose set forth. 85

3. The combination with a valve casing having a channel extending therethrough, of means for delivering fluid under pressure to said channel, means for conducting fluid from the casing, a drain, a valve controlling communication between the casing channel and drain, and an ejector having valve communication with the fluid delivery means and adapted for drawing fluid from the casing channel and delivering same to the drain. 95

4. The combination with a valve casing having a channel extending therethrough, of means for delivering fluid under pressure to said channel, primary and secondary conduits opening independently from said channel and adapted for different duty, means for priming the secondary conduit during the action of the primary conduit, a valve operable from the pressure of the primary conduit for establishing a flow of fluid through the secondary conduit, a manually operable drain valve for draining the primary and secondary conduits and an ejector operable from said casing channel for accelerating the flow of liquid through said drain valve. 100

5. The combination with a valve casing having a channel extending therethrough, of means for delivering fluid under pressure to said channel, primary and secondary conduits opening independently from said channel and adapted for different duty, a valve operable from the pressure of the primary conduit for equalizing the pressure between the primary and secondary conduits, a manually operable drain valve for draining said conduits and an ejector operating from said casing channel for accelerating the flow of liquid through said drain valve. 110

6. The combination with a set of hydraulic cylinders, of a pump and a valve for delivering fluid under pressure thereto, having a main channel and separate conduits leading 5 therefrom to each of said hydraulic cylinders, means for delivering fluid under pressure to one of said cylinders until it has reached its limit and accumulates pressure in the conduit, an automatic valve operable 10 from such accumulated pressure for establishing a flow of fluid to other of said hy-

draulic cylinders, a manually operable drain valve for draining said cylinders and conduits and an ejector operable from the pump for accelerating the flow of fluid through 15 said drain valve.

In testimony whereof I affix my signature in presence of two witnesses.

JOHN J. SIMMONDS.
